UNITED STATES PATENT OFFICE

1,924,044

CONCRETE SAFETY MINING UNIT

John MacDougall, Wyoming, Pa.

Application December 30, 1930
Serial No. 505,591

1 Claim. (Cl. 72—72)

This invention relates to a pillar for supporting roofs of mines so that all the coal can be removed from the mine without leaving portions to form supporting pillars, the general object of

5 the invention being to provide a plurality of units for forming the pillar, the units being so formed that they can be assembled by unskilled labor and the pillar made of any desired height, and the units being of such material that there is no

10 danger of the pillar deteriorating.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:—

Figure 1 is an elevation of a pillar constructed in accordance with the invention.

25 Figure 2 is a perspective view of a modified form of pillar.

Figure 3 is a perspective view showing one of the units provided with reinforcing means.

Figure 4 is a sectional view through the hollow pillar shown in Figure 1.

30 Figure 5 shows in perspective a number of the blocks forming the hollow pillar.

Referring to the drawing in detail, the pillar shown may be formed hollow as in Figures 1 and 4 and in this case each unit is composed of the four blocks 1', the blocks at opposing sides being longer than the blocks at the other sides so that the short blocks will fit between the ends of the long blocks. The units of the hollow pillar are also alternately arranged, as shown in Figure 2. Each block is formed with the projections 3 on its lower face for engaging recesses 4 on the upper face of an under block so that the blocks are locked together by the projections and recesses. As shown in Figure 5, projections on a long block engage recesses in the long blocks located under the first mentioned long blocks, with the projections on the short blocks engaging recesses in the long blocks located under them and with projections on the long blocks placed over the

short blocks engaging recesses in said short blocks. Thus all the blocks are firmly locked together and there is no danger of the units slipping out of place.

Any suitable kind of mortar or molder's loam 60 can be placed between the blocks and this acts as a cushion and binder for the parts.

A filling of rock or any other suitable material can be placed in the hollow pillar, as shown at 5 in Figure 4 and the blocks may be provided 65 with reinforcing steel, as shown at 6 in Figures 3 and 4.

This pillar, as before stated, supports the roof of a mine and enables the removal of coal which has hitherto been left to form pillars. As the 70 pillars are made of reinforced concrete, there is no chance of disintegration as there is when the pillars are formed of coal or wood and thus there is no danger of the roof collapsing after a course of time.

75 It is thought from the foregoing description that the advantages and novel features of the invention will be readily apparent.

It is to be understood that changes may be 80 made in the construction and in the combination and arrangement of the several parts, provided that such changes fall within the scope of the appended claim.

What I claim is:—

85 A concrete safety mining unit comprising a pillar formed of a plurality of block-like units imposed one upon the other to provide uniform straight vertical walls to the pillar at all sides thereof, each unit composed of a plurality of long and short blocks, the blocks of each unit being placed in a row and the blocks of the next unit placed at right angles to the blocks of the first unit whereby the units are alternately arranged with the blocks of alternate units extending at right angles to the blocks of the other units, 90 lugs formed on the lower face of each block, each block having recesses in the upper face, whereby the said blocks are locked together by the interfitting of the lugs in the recesses, reinforcements 95 in the respective blocks, and a bonding material arranged between the blocks, the lugs and recesses being of corresponding sizes with respect to each other and of wedge formation.

JOHN MACDOUGALL.
